3 Claims. (Cl. 18—8)

This invention relates to an improved extrusion apparatus for use in shaping of structures from solutions of synthetic polymers. More particularly, this invention relates to an improved sealing and filtration means in an extrusion apparatus for use in the shaping of fibers and films from solutions of synthetic polymers.

Shaping of structures such as fibers and films from solutions of synthetic polymers generally requires use of very small extrusion orifices, across which a large pressure drop is taken. Such a large pressure drop is necessary to assure a uniform distribution of flow to each hole in a spinneret as in fiber spinning and along the entire length of a slot in casting of films.

Filters of various types immediately upstream from the extrusion orifice are also necessary to assure presentation of a clean solution to the orifices. Such filters entrap particulate matter at a point sufficiently remote from any extrusion orifice that cross-flow of solution can occur downstream therefrom and prevent disproportionate solution flow from the extrusion assembly.

Adequate filtration can be provided, depending on the quality of the solution or melt to be shaped and on the orifice employed, by use of a metallic wire screen of suitable pore size or by use of a woven fabric or felt cloth of natural or synthetic fibers. When fibrous filters are used, a metallic wire screen is generally employed as the final element in a filtration assembly to provide mechanical support for the fibrous filters and to provide for cross-flow of solution immediately upstream from the extrusion orifices which assures a uniform supply of solution thereto.

The metallic wire screen edges must be sealed to the extrusion apparatus. This is necessary to prevent bypassing of unfiltered solution. Heretofore, such sealing has taken the form of an elastomeric or deformable metallic gasket molded to or mechanically crimped around the edges of the screen. Neither of these means is completely satisfactory. The former contributes to orifice plugging as they disintegrate under solvent attack. The latter will not recover from the deforming compression.

When it is desired to incorporate the separate characteristics of two individual polymeric species into one filamentary structure, it is frequently advantageous to spin the two polymeric species in such a way that each species remains separate and distinct within a different area of the fiber cross section. This is particularly true when the differences in properties of the two species are such as to produce a crimped fiber when the two species are spun in eccentric relationship to each other. For example, when two polymeric species having different shrinkage characteristics appear in eccentric relationship to each other in a single fiber, that fiber will develop a desirable spiral-type crimp when it is treated under conditions which cause the two components to shrink.

Various embodiments of apparatus for producing composite or side-by-side fibers from two separate solutions or melts which are capable of forming fibers on evaporation, coagulation, or cooling are described in U.S. Patent 3,006,028. However, such apparatus has not proved to be satisfactory in providing fibers having a high degree of uniformity of distribution of components in the fiber structure since it would impractically difficult to utilize elastomeric seals to provide a positive seal between the

2

solution dividers of the back plate and the face of the extrusion plate. Lack of such a gasket allows premature intermixing of the solutions causing the formation of homopolymer fibers instead of bicomponent polymeric fibers or films.

It is, therefore, an object of this invention to provide an improved apparatus for filtration of synthetic polymer solutions prior to extrusion through shaping orifices in an extrusion assembly.

10 Another object is to provide an apparatus capable of producing a positive seal between the back plate and the face of the extrusion plate.

15 A further object is to provide an improved apparatus for cross-flow of solution immediately upstream from the extrusion orifices which assures a uniform supply of solution thereto.

These and other objects will become apparent in the course of the following specification and claims.

20 The objects of this invention are accomplished by an extrusion apparatus for producing shaped structures which comprises a back plate having at least one polymer receiving chamber, an extrusion plate having at least one orifice positioned in such a manner as to provide communication between said back plate chamber and said extrusion plate orifice, a fine mesh metallic sealing means positioned in compressed contact between said back plate and said extrusion plate to provide a positive seal between said back plate and said extrusion plate and to provide for filtration of materials prior to their entrance into said 25 extrusion plate orifice, and conduit means having at least one channel, said channel being associated in such a manner with said back plate chamber for introducing filament-forming materials into the said chamber.

30 This invention will be further illustrated by reference to the accompanying drawing in which:

FIGURE 1 represents a sectional view of one form of the improved apparatus according to this invention.

FIGURE 2 is an enlarged sectional view of the encircled section of FIGURE 1.

35 FIGURE 3 is an enlarged cross-sectional view similar to that of FIGURE 2 but illustrating modification to the apparatus of that figure to provide for spinning of filaments comprising two different synthetic polymeric materials.

40 FIGURE 4 is a schematic view of a portion of the face of the extrusion plate of FIGURE 1, illustrating the approximate proximity of extrusion orifices contained therein.

45 With reference to FIGURE 1, the fluid fiber forming polymer substance either as a melt or in the form of a solution is delivered through conduit 1 into chamber 2 above optional filter pack 3. After passage through the filter pack 3, if used, and multiple conduits 4, the polymer is filtered through die-cut screen 5 and extruded from 50 multiple orifices 6.

55 As detailed in FIGURE 2, screen 5 is compressed at points Y and Z between extrusion plate 7 and back plate 8 sufficiently to be made impervious to the polymer at two concentric circles of contact. In this manner, bypassage of the screen by unfiltered solution is effectively prevented.

60 FIGURE 3 illustrates modifications to the detail of FIGURE 2 for spinning of two-component composite filaments from three concentric rings of orifices. Polymer A, as designated in the drawing of FIGURE 3, is delivered through conduits, not shown, to two annular distribution channels 9, while polymer B, as designated in the drawing of FIGURE 3, is delivered to two other annular distribution channels 10. The two polymers alternate with each other radially within the extrusion assembly. Polymer dividers or septa 13, which are in-

tegral parts of back plate 8, are accurately machined to bear simultaneously on screen 5 as the flat inner face of extrusion plate 7 is pressed into position against the screen by retaining ring 14 and washer 15. By careful control of over-all extrusion assembly dimensions and of rigidity of the extrusion plate 7, the necessary compression of the screen 5 to form an impermeable seal in the required multiplicity of circles is achieved.

In operation, two separate spinning solutions or melts are fed through metering pumps, not shown, into distribution channels 9 and 10. Each polymer has complete freedom of cross-flow within the bounds of its chamber. The polymer then flows into the individual slots 12 which are centered over extrusion plate orifices 11. The two polymers merge at substantially the center of slots 12 and are extruded as a side-by-side composite filament from orifices 11.

Various modifications of the apparatus shown in FIGURES 1, 2, 3 and 4 may be used in combination with the extrusion plate of the present invention. For example, the separators or septa need not be in concentric rings as shown in the drawings, however, concentric rings are preferred, as in fiber spinning; whereas, concentric rings would not be preferred in film extrusion.

In apparatus having a number of concentric septa, the extrusion plate may be cup-shaped as shown in the drawings, or may be in the form of a flat plate. The extrusion plate can be supported at its center as well as around its periphery. If additional filtration of the spinning solutions or melts is desired, distribution channels 9 and 10 may be provided with filtering material.

The number of septa is likewise not critical. However, it has been found that the improved sealing means of this invention provides the greatest improvement in uniformity of the distribution of components in apparatus having a plurality of concentric septa.

The materials of construction of the screens are not critical and may be selected from any materials that are known to be satisfactory for the extrusion of either of the solutions or melts, such as titanium or stainless steel. In the case of acrylonitrile polymer solutions, it is generally desirable to use apparatus constructed of Type 316 stainless steel because this material shows a very low degree of corrosion under operating conditions. The essential requirement is that the screen be compressible to an essentially impervious structure by forces which can be developed in assembly of the extrusion apparatus. For example, a compression of .005" is adequate to prevent cross-flow of solution through a stainless steel screen of 200 mesh made of .0023" diameter wire and woven in a twill pattern. A twill weave stainless steel screen of 200 x 1500 mesh, identified as "Micromesh," No. 15M10 and made by Multi-Metal Wire Cloth Co. become impervious to spinning solution when compressed only .002." Greater compressions are feasible, but the minimum compression which gives a good seal is preferred in order to minimize the structural requirements imposed by high screen compressions on the extrusion apparatus.

The apparatus of this invention is useful in producing homo or single-component fibers or films or composite fibers or films of two components having a high degree of uniformity with regard to the amount of each com-

ponent present in each fiber. In producing single-component fibers or films, the advantages of this invention are found in the convenience and economy of extrusion assembly maintenance. In producing bicomponent fibers, the advantages are found in the provision of a large number of short length seals between the extrusion plate orifices and the septa of the back plate, heretofore, impractically difficult to achieve, to prevent premature intermingling of the two solutions or melts.

Although the invention has been illustrated in its application to processes for spinning of fibers from polymer solutions or melts, it obviously has utility and may be employed in solution or melt-casting of films, particularly in processes for the production of fine gauge films which employ narrow extrusion orifices, without departing from the spirit and scope of the invention.

What is claimed is:

1. An extrusion apparatus for producing shaped structures which comprises a back plate having separate chambers therein, an extrusion plate having at least one orifice positioned in such a manner as to provide communication between said back plate chambers and said extrusion plate orifice, a fine mesh metallic screen positioned in compressed contact between said back plate and said extrusion plate to provide a positive seal between said back plate and said extrusion plate and to provide for filtration of materials prior to their entrance into said extrusion plate orifice, septa dividing the space between said extrusion plate and said back plate chambers into a plurality of separate zones, said septa having a length relative to said back plate sufficient to compress said screen to provide a positive seal between adjacent zones above said screen and to allow communication with each other at a point below said screen and contiguous to said orifices, and conduit means having at least two separate channel systems, each such system being associated with at least one of the said back plate chambers for introducing filament-forming materials into each of the separate chambers.

2. The apparatus of claim 1 wherein said metallic sealing means is made of stainless steel.

3. The apparatus of claim 1 wherein said metallic sealing means is made of titanium.
